[57] CLAIM

The ornamental design for a file assembly, substantially as shown and described.

DESCRIPTION

FIG. 1 is a front elevational view of a file assembly showing my new design;
FIG. 2 is a right side elevational view thereof;
FIG. 3 is a rear elevational view thereof;
FIG. 4 is a left side elevational view thereof;
FIG. 5 is a top plan view thereof;
FIG. 6 is a bottom plan view thereof;
FIG. 7 is a front elevational view of a modified form of the design shown in FIGS. 1 through 6;
FIG. 8 is another modified form of the design shown in FIGS. 1 through 6;
FIG. 9 is a third modified form of the design shown in FIGS. 1 through 6;
FIG. 10 is a front elevational view similar to what is shown in FIG. 1, but with the front panel member removed;
FIG. 11 is a right side elevational view thereof;
FIG. 12 is a rear elevational view thereof;
FIG. 13 is a left side elevational view thereof;
FIG. 14 is a top plan view thereof;
FIG. 15 is a bottom plan view thereof;
FIG. 16 is a front elevational view of the closure plate member of the design shown in FIGS. 1 through 6;
FIG. 17 is a right side elevational view thereof;
FIG. 18 is a top plan view thereof;
FIG. 19 is a rear elevational view thereof;
FIG. 20 is a left side elevational view thereof; and
FIG. 21 is a perspective view of the design shown in FIGS. 10 through 15 shown on a reduced scale.
